UNITED STATES PATENT OFFICE

ARTHUR BATES, OF LEICESTER, ENGLAND, ASSIGNOR TO UNITED SHOE MACHINERY CORPORATION, OF PATERSON, NEW JERSEY, A CORPORATION OF NEW JERSEY

METHOD OF AND MACHINE FOR SOLE FITTING

Application filed May 14, 1929, Serial No. 362,964, and in Great Britain June 1, 1928.

This invention relates to improved methods of sole fitting and to improvements in sole fitting machines. The improved sole fitting machine herein illustrated is a channeling machine of the type in which an unattached sole is fed continuously past channeling means by co-operating upper and lower feed wheels which progressively engage opposite sides of the sole margin, such machines being commonly employed for channeling, or for channeling and grooving, outsoles for McKay-sewed shoes or shoes in which both an insole and an outsole are otherwise directly secured to the upper. The illustrated machine, however, is also adapted to perform upon a sole (and more particularly but not exclusively upon an outsole) in combination with the channeling operation, or independently thereof, an edge-thickness reducing, feathering or fleshing operation.

In the channeling of outsoles for shoes of the above type, two well-known types of channels are employed, namely, that known as the English channel or bottom channel and that known as the American channel or edge channel. The so-called English channel is cut from the grain or outer surface of the sole and extends toward the opposite or flesh side of the sole. The cross-sectional shape of the English channel is dependent upon the shape of the particular knife employed, the knives commonly used being practically straight-edged at the tip but being curved adjacent to that portion which cuts into the sole surface, so as to produce a channel lip with a blunt and rounded edge. The so-called American channel is cut by a knife which is straight-edged throughout its length, the cut extending inwardly from the sole edge toward the middle of the sole and usually being approximately parallel with the sole surface.

The base of an English channel is usually farther from the grain surface of the sole than the base of an American channel, in soles of the same type and thickness, so that the strength of the material at the sewing point is liable to be less in an English-channeled sole than in an American-channeled sole. Accordingly the employment of an

American channel is advantageous where it is of importance to have maximum strength at the sewing point. In cases where the shank portions of soles are to be feathered to give the appearance of lightness, there is a further reduction of strength at the sewing point if an English channel is formed in the shank, and in such cases the use of an American channel in the shank is also distinctly advantageous. It is sometimes found, however, that the American channel does not remain permanently closed so well as the English channel and accordingly, notwithstanding the above-mentioned advantages of the American channel, there are obvious advantages in the employment of an English channel in the tread portion or forepart of the sole where the channel flap is particularly subject to wear and to contact with damp pavements. Accordingly, some manufacturers at the present time are channeling the foreparts of soles with an English channel and the shank portions of the soles with an American channel, one practice being to channel the shank of a sole at one side in one machine, then to channel the whole of the forepart of the sole in another machine, and then to return the sole to the first machine and to channel therein the other side of the shank. Another method which is also in use is to channel the shank, first on one side and then on the other side and thereafter by means of one machine to channel the forepart by means of a second machine, but with this method the joining of the dissimilar forepart channeling and shank channeling at the completion of the forepart channeling operation is not only difficult but frequently the sole is damaged by the joining operation so as to mar its appearance in the finished shoe.

The method of channeling a shoe with an English channel or bottom channel in the forepart and an American channel or edge channel in the shank, hereinafter referred to as "two type channeling", has the advantage that the forepart or tread portion of the shoe, which is subject to wear and to contact with damp pavements, is channeled with that type of channel (i. e., a channel in its tread face

or a so-called bottom channel) which can be most readily closed and is most likely to remain permanently closed, while the shank portion of the shoe, which is not subject to wear, is provided with an American or edge channel whereby substantial feathering (or shank reducing) and the consequent production of a light edge at that part is made practicable without unduly weakening the seam.

10 A further advantage of an American channel in the shank is that, in the case of Louis-heeled shoes, the channel may be made to blend readily with the flap since the flap and the channel lip may both readily be made of the same thickness where they join.

In view of the foregoing it is one object of the present invention to provide for channeling a sole with a bottom or face channel at one part of the sole and an edge channel at another part of the sole at a single continuous operation, thus doing away with the necessity for practicing the present expensive method of transferring a sole from one machine to another when the sole is to be channelled with two types of channeling.

To the accomplishment of the above object, the invention, in one aspect, provides a novel method of sole channeling which consists in relatively moving a sole and means for channeling a sole to form a continuous channel in the sole, and changing the relation between the sole and the channeling means during the continuous channeling operation in such a manner as to effect face or bottom channeling in one portion of the sole and edge channeling in another portion of the sole. This method may be carried out, in accordance with one exemplification herein set forth, by the use of a knife substantially like a regular English channel knife, and by feeding a portion of the sole margin past the knife while the knife is positioned so that its straight tip portion only will cut inwardly from the sole edge to form an American channel in the sole margin, and subsequently tilting the knife to position it so that its curved portion becomes effective to cut inwardly from the grain surface of the sole, and continuing to feed the sole past the knife to form an English channel in another portion of the sole margin, the feed of the sole continuing also during the tilting of the knife so that the knife cut will extend across the corner of the sole edge and a gradual and even blending of the American and English channels will be effected. As illustrated, the above-described tilting of the knife takes place at the junction between the shank and forepart at one side of a sole and a similar tilting of the knife, but in the opposite direction, takes place at the junction of the forepart and shank at the other side of the sole so that an American channel is formed at both sides of the shank and an English

channel is formed around the forepart of the sole.

Another object of the invention is to provide an efficient and reliable machine for effecting two-type channeling of a sole in a single continuous operation.

With this object in view the invention resides in the provision, in a channeling machine, of means for forming a continuous channel in a sole, and means for relatively adjusting the sole and the channeling means during the continuous channeling operation in a manner to produce a bottom channel, i. e., a channel in one side face of the sole, in one portion of the sole margin and an edge channel, i. e., a channel in the edge face of the sole, in another portion of the sole margin. In the illustrated machine co-operating upper and lower feed wheels are arranged to feed an unattached sole past channeling instrumentalities which, in accordance with one embodiment of the invention, comprise two knives, viz., a straight-edged knife hereinafter called an "American" knife, and a curved knife hereinafter referred to as an "English" knife. In this embodiment of the invention the illustrated knives are both mounted upon a single knife carrier which is mounted with provision for tilting adjustment and upon which the American knife is mounted for sliding movement to and from position to operate upon the sole. The illustrated knife carrier is tiltable about a center so located with respect to the sole that tilting of the knife carrier will shift the English knife edgewise of the sole so as to cause the knife to cut across the corner of the sole edge. Treadle mechanism is provided whereby the knife carrier may be tilted at the will of the operator and as hereinafter explained the knife carrier is first tilted upwardly, after an American channel has been cut in the sole edge at one side of the shank, to position the English knife for cutting an English channel in the grain side of the sole around the forepart, after which the knife carrier is tilted downwardly to reposition the knives for cutting an American channel in the sole edge along the opposite side of the shank portion of the sole. Also, as illustrated, provision is made for retracting the American knife from the sole when the knife carrier is tilted upwardly so that the American knife will not interfere with the cutting of the English channel around the forepart of the sole and for returning the American knife into operative position when the knife carrier is tilted downwardly to resume the cutting of an American channel in the shank of the sole. In accordance with alternative embodiments of the invention, however, the American channel knife may be omitted and the English knife (or a modification thereof) alone employed to cut both the American and the English channels.

As already indicated it is often the custom to perform a shank-reducing operation upon a sole in order to give the appearance of a light edge in the shank. It is also the custom with many manufacturers to perform a feathering operation around the forepart of the sole but in such cases the feathering operation is frequently not intended primarily as a thickness-reducing operation but is intended merely to "flesh" the surface (i. e. to remove shreds of leather from the surface) without reducing the thickness of the sole to any substantial extent.

To adapt the illustrated machine to perform the shank reducing and fleshing operations just referred to the machine is further provided with a feather-edging knife arranged to bevel or scarf the sole margin at the flesh side thereof, this knife being adjustable at the will of the operator to vary the angle of the bevel or scarf produced by the knife and thereby to vary the thickness to which the edge of the sole is reduced. Another feature of the invention, accordingly, is to be recognized in the provision, in a machine for operating upon soles, of adjustable sole edge reducing means, and mechanism for adjusting the reducing means during the operation of the machine to vary the extent of sole edge reduction independently of any variation in the thickness of the sole. As illustrated, the edge reducing means comprise a skiving knife mounted with provision for tilting adjustment and connected with the mechanism for tilting the channeling knives so that when the latter are tilted to change the type of channeling the skiving knife will also be tilted to vary the extent of sole edge reduction. In the illustrated machine, also, the arrangement is such that the skiving knife is also tilted so that, independently of the above-described tilting of the skiving knife the knife also is tilted upon variation in the thickness of the sole margin to maintain uniform the thickness of the sole edge produced by the edge reducing operation.

Referring to the drawings,

Fig. 1 is a view, in front elevation, of so much of a so-called McKay channeling machine as is necessary to illustrate the application of the present invention thereto;

Fig. 2 is a view similar to Fig. 1 but showing the channel knives in a different position;

Fig. 3 is a front elevational view on a reduced scale of certain of the parts shown in Figs. 1 and 2 and of certain other parts including a feather edging knife;

Fig. 4 is an end elevational view as seen from the left of the machine of certain parts shown in Fig. 3;

Fig. 5 is a fragmentary cross-sectional view of the forepart of a sole showing an English type channel formed in the margin of its grain side and showing the margin of its flesh side scarfed or feathered;

Fig. 6 is a fragmentary cross-sectional view of the shank portion of the sole shown in Fig. 5, showing an American type channel cut inwardly from the sole edge and showing the sole margin reduced by scarfing or feathering to a greater extent than in Fig. 5;

Fig. 7 is a detailed elevational view, partially broken away, of a channel knife having a grooving knife attached thereto;

Figs. 8 and 9 are conventional views of a modified form of channel knife showing the knife in different positions and illustrating the mode of operation of the knife upon a sole; and

Figs. 10 and 11 are conventional views illustrating alternative means for the purpose of effecting two-type channeling.

The machine which has been selected for illustrative purposes is a machine of the type known as a McKay channeler, such a machine being disclosed, for example, in United States Letters Patent No. 663,050, granted Dec. 4, 1900, upon application of C. P. Stanbon. The illustrative machine comprises a frame 10, a lower feed wheel 12 carried by a horizontal feed wheel shaft 14, an adjustable edge gage 16 (Fig. 2), and an upper feed or presser wheel 18 carried by a shaft 20 (Fig. 3) journaled in a head 22 which is normally pressed downwardly against a stop 24 on the frame 10 arranged to prevent the two feed wheels from actually engaging each other. The head 22 with the upper feed wheel 18 is adapted to be raised by means of a treadle (not shown) to permit a sole to be inserted between the feed wheels and treadle mechanism (not shown) may be employed for adjusting the edge gage transversely of the direction of work feed while the sole is being fed to determine the depth and location of the channel. The above-described parts, with the exception of the edge gage, are of substantially the same construction and they are operated in the same manner as corresponding parts disclosed in the above-mentioned Letters Patent No. 663,050, to which reference may be had for details of construction not herein specifically described.

The illustrated edge gage 16 is supported by a slide 17 by means of which it may be adjusted while the sole is being fed. The gage 16 is mounted upon the slide 17 with provision for horizontal adjustment independently of its adjustment by means of the slide 17.

In the machine shown in Figs. 1 and 2, the channeling means comprises two channel knives 36 and 44, the knife 36 being shaped substantially like the usual so-called English channel knife while the knife 44 is shaped like the usual so-called American channel knife. In Fig. 1 the two knives are shown as co-operating in the cutting of an American channel and in Fig. 2 the knife 36 alone is shown as operating independently of the

knife 44 to cut an English channel. It is to be understood, however, that, if desired, the knife 44 may be omitted and the knife 36 only (or preferably a somewhat modified 5 form of this knife such as that shown in Figs. 8 and 9) may be employed for the cutting of both American and English channels in the same sole.

For the purpose of enabling the knives 10 36 and 44 to be used in the cutting of both American and English channels in a sole, these knives are both supported by a knife carrier 28 (Figs. 1 and 2) of improved construction which is employed in place of the 15 channel knife carrier of the machine shown in the patent referred to. The improved knife carrier 28 herein shown is formed at the lower end of a slide 30 (Fig. 3), which is mounted for up-and-down adjustment in 20 a guideway in the head 22, a screw 31 being provided by which this adjustment may be effected. The knife carrier 28 is provided with an arcuate guideway 32 curved about a center indicated at 33 in Fig. 1. In the guideway 32 there is mounted for movement a 25 knife segment 34 upon which is fixed a channel knife 36 having its edge curved (except for a relatively short straight portion at the tip of the knife), to form the usual English-type channel. The surface of the knife segment 30 34 remote from the center of its guideway is provided with gear teeth 38 (Fig. 1) that mesh with the teeth of a toothed segmental rocker 40 fixed to a spindle 42 carried by bearings on the knife carrier 28. The 35 above-described arrangement of parts is such that when the English channel knife 36 has been moved by rotation of the rocker 40 into the position shown in Fig. 2 it is effective to 40 cut an English-type channel in a sole positioned between the feed wheels 12 and 18 and against the edge guide 16, but when the knife 36 has been moved into the position shown in Fig. 1 it is somewhat withdrawn from the 45 path of the sole so that its curved portion is retracted from the path of the work while its straight tip portion lies in the path of the channel knife 44 which has a straight blade adapted to cut an American-type channel. 50 In other words when the knife 36 is positioned as shown in Fig. 1, its tip is no longer appreciably sloped but is practically parallel to the sole surface.

To enable the rocker 40 and the knife segment 34 to be moved into the two positions above referred to, the spindle 42 is extended rearwardly of the knife carrier 28 and fixed to this rearward extension is a lever arm 46 which is connected to the upper end of a treadle rod 48. The lever arm 46 is normally held in an upwardly extending position by means of a treadle spring 50 arranged to press upwardly upon the treadle rod 48. Upward movement of the lever arm 46 (under 55 the influence of the treadle spring 50) is lim-

ited by an adjustable stop 52 and downward movement of the arm 46 (under action of the treadle) is limited by an adjustable stop 54, the stops 52 and 54 being carried by lugs extending from the rear of the knife carrier 70 28. The stop 52 may be adjusted to vary the location of the American channel widthwise of the sole edge while the stop 54 may be adjusted to vary the location of the English channel inwardly from the sole edge. 75

The aforementioned knife segment 34 is provided with a straight guideway 58 (approximately horizontal when the lever arm 46 is in contact with the upper adjustable stop 52 as indicated in Fig. 1) in which is 80 mounted for reciprocation, toward and from the edge of a sole positioned in the machine, a slider 60 which carries the aforesaid straight-edged channel knife 44 adapted to co-operate with the knife 36 in cutting an 85 American channel. The straight guideway 58 and the edge of the straight-edged knife 44 are both parallel to the straight portion of the edge of the curved channel knife 36. An upstanding ear 62 on the slider 60 is pivotally 90 connected, by means of a link 64, with one end of a lever 66 that is fixed to the front end of the spindle 42. The arrangement is such that rotation of the segmental rocker 40 in a direction to move the English channel knife 36 to the position shown in Fig. 1 will advance the straight channel knife 44 into the path of the sole (as indicated in Fig. 1) as the knife 44 is being swung and retracted into said position by the knife segment 34 during the movement of the latter. 95

While manual means has been shown and described for shifting the positions of the channeling knives the invention is not limited to the provision of channel knife shifting means which is either wholly or partially under the control of the operator. 105

The aforementioned center 33 about which the arcuate guideway 32 for the knife segment 34 is curved is so located (for the particular shape of knife herein shown) that when the English channel knife 36 is swung to position for co-operating with the straight knife for cutting an American channel the knife 36 is also somewhat withdrawn from 110 the sole so that its curved portion is ineffective during the cutting of the American channel. 115

The operation of the machine thus far described is as follows: An unattached outsole 120 A (Fig. 6) is entered between the feed wheels 12 and 18 in the manner usual in McKay channeling machines, the sole lying in a horizontal plane. The straight portion of the English channel knife 36 is horizontal and the American channel knife 44 is also horizontal and is in the same plane as the straight portion of the English channel knife and behind it, regarded in the direction of feed (see Fig. 1). The operator starts the machine and 125 130

the two knives cut an American channel (shown at B, Fig. 6) in the shank portion of the sole, the English knife cutting the marginal portion of the channel because it is in front (regarded in the direction of feed) of that part of the edge of the American knife which is nearest the sole edge face (see Fig. 1). At this time the curved portion of the English knife 36 is withdrawn so that it does not cut. When the junction of the shank and forepart is reached the operator depresses the treadle with the result that, as the sole continues its travel, the American knife 44 is gradually withdrawn by a lateral tilting movement completely from contact with the sole and the English knife 36 is gradually tilted about the center 33 and moved inwardly edgewise of the sole so that as shown in Fig. 2 not only is the angular position of the knife changed but the knife is also moved sufficiently toward the middle of the sole to make the curved English channel cut shown at C in Fig. 5. The result of this adjustment of the knife 36 is to modify the shape of the channel cut in the vicinity of the ball line so that when the English channel has been made at the forepart of the sole the American channel B and the English channel C will be blended together. When the shank is reached at the other side of the sole the treadle is released and a reverse tilting of the knife 36 takes place for the purpose of forming a blend between the English channel in the forepart and the American channel in the shank portion at this side of the sole.

For the purpose of reducing the thickness of the sole edge the illustrated machine is also provided with a knife constructed and arranged to remove a chip from the marginal portion of the sole (for instance from the edge of one of its faces) and provision is also made for changing the inclination of the knife during the operation of the machine. While the mechanism for effecting edge thickness reduction is herein shown in combination with channeling means it is within the scope of the invention to provide a machine adapted for reducing the thickness of the edge of a sole without performing any other operation upon the sole.

As shown in Fig. 4, a bracket 71 is bolted to the frame 10 and to the upper end of the bracket is fixed a carrier 73. In order to provide for vertical adjustment, the carrier 73 is connected to the bracket 71 by a tongue-and-groove connection and can be adjusted vertically by turning the knob 75 of a screw 77, after which the carrier 73 may be gripped in adjusted position by tightening a bolt 79.

At the rear of the carrier 73 is a bearing for the reception of a vertical pivot-pin 81 to the upper end of which is fixed an oscillating bracket 83 that is provided with bearings for a horizontal spindle 85. To the front end of the spindle 85 is fixed a knife-clamp

87 in which is secured a reducing or feathering knife 91, the cutting edge of which lies behind the channeling knives.

The left-hand end (as viewed in Fig. 3) of the plane edge of the illustrated feathering knife 91 is located in the line of the axis of the spindle 85, so that when the spindle is turned on its axis (as will be described later) the edge of the knife will rotate about its left-hand end. In practice the left-hand end of the edge of the feathering knife is sometimes extended and turned down towards the feed wheel 12, or it may actually extend between the adjacent rows of the teeth of the feed wheel. By raising or lowering the carrier 73 the axis of the knife-carrying spindle 85, and therefore the axis of rotation of the feathering knife 91, may be correspondingly raised or lowered to facilitate adjustment of the knife. Further, by extending the edge of the feathering knife 91 to the left of its axis of rotation that extended part of the knife will be lowered when the main portion of the knife is raised by rotation of the knife about its axis.

In order to limit the inward swing of the feathering knife 91 into operative position and so to define the said operative position laterally, a lug 89, depending from the oscillating bracket 83, is adapted to contact with an adjustable stop 93 on the carrier 73. When the knife 91 has been swung into operative position its oscillating bracket 83 is clamped by means of a bolt 95. When it is desired to sharpen the knife 91 the bolt 95 is released and the oscillating bracket 83 is swung in a clockwise direction to move the knife 91 towards the observer (as viewed in Fig. 4) into a position in which it can readily be removed from the knife clamp 87.

In order to provide for the desired movement of the feathering knife 91 the following mechanism is provided. Fixed to the feathering-knife-carrying spindle 85 by an approximately upright pivot pin is a short lever 101 having a ball end (Fig. 3). The ball end of the lever 101 is received in a U-shaped socket on the end of a lever 103 that is fixed on a pivot pin 105 mounted (eccentrically for adjustment) in a bearing in the top of a bracket 107 fixed to the rear of the frame 10 of the machine. The segmental rocker spindle 42 (which, as already described, is carried by the head 22) has fixed to it, near its rear end, a bent lever 109 to which is adjustably connected, by a screw 111, the upper end of a link 113, the lower end of which is pivoted to the lever 103.

It will be observed that, as a result of the above-described construction and arrangement, the feathering knife 91 will be rocked slightly about its axis of movement (i. e., about its left-hand end in the particular construction being described) if there is a change in the thickness of the work as the latter pro-

gresses through the machine; if the work becomes thicker the upper feed or presser roll 18 will rise and will carry upwardly with it the left-hand end of the head 22 and consequently the spindle 42, which latter in turn will, through the link 113, rock the lever 103 upwardly and the lever 103 will, through the lever 101, rock the feathering knife 91 to increase the amount of edge thickness reduction. The various parts are so proportioned, connected and adjusted that, unless manually moved as will be described hereinafter, the feathering knife will always reduce the edge of the work to a definite uniform thickness irrespective of the variations in the thickness of the edge of the work before being acted upon by the knife.

It will further be observed that if the spindle 42 be oscillated (as occurs under action of the treadle mechanism in changing from an American to an English channel and vice versa) this will also cause a rocking of the feathering knife; the construction and arrangement are such as to give around the fore-part, in conjunction with the English channel, a very small reduction in the thickness of the edge of the work (little more indeed than sufficient to remove projecting shreds of leather) and to give at the shank, in conjunction with the American channel, an appreciable reduction in the thickness of the edge of the work so as to produce there a so-called light or thin edge shank. Thus, through the action of the treadle mechanism above referred to, the angle of the feathering knife may be adjusted by the operator to vary the amount of sole edge reduction while the machine is running at normal speed. In Figs. 5 and 6 the parts of the sole indicated by dotted lines and marked D and E are the chips or trimmings that are removed from the forepart and the shank respectively by the use of a particular feathering knife adjusted in a particular way (the effective left-hand end of the cutting edge of the feather knife being in line with its axis of rotation) in the illustrative machine.

Many manufacturers desire a wide and shallow feathering scarf round the forepart of the sole (as the scarf D, Fig. 5) and a narrow and deep scarf in the waist, this latter scarf being as deep as or deeper than the scarf E in Fig. 6 and about half or less than half the width of that scarf. Such a result can be obtained by the use of a feathering knife that extends about equally on each side of its axis of rotation (the cutting edge of the knife passing through the line of the said axis), by adjusting the carrier 73 so that the said axis is slightly below the level of the top of the feed wheel 5 (i.e. below the bottom surface of the sole to be feathered), and by adjusting the edge guide 7 so that the edge 65 of the sole will be at the correct distance to

the right of the said axis. Such a modified form of feathering knife as that above referred to is indicated in Fig. 3 by the dotted lines 76 in conjunction with the full lines 70 of the knife 91.

It is to be observed that the carrier 73 can be raised or lowered to bring the axis of rotation of the feathering knife on, above or below the level of the feed wheel 12 (i.e. of the bottom of the work); that there may be 75 used a feathering knife of such a width that the left-hand end of its edge may extend (laterally of the machine) to, short of, or beyond its axis of rotation; that the aforementioned edge gage can be adjusted laterally of the machine to vary the position in the machine of the edge of the work; and that by adjusting the screw 93 the operative position of the feathering knife about its pivot 81 may be varied. By means of these adjustments a considerable variation in edge-thickness reducing at forepart and shank may be obtained and it is believed that all variations usually demanded by manufacturers can be obtained by suitable variation of these 90 variables.

If it be desired to provide for grooving in addition to channeling this can readily be done in the illustrative machine. One convenient construction providing for waist 95 grooving is indicated in Fig. 7. The shank 121 of the American channel knife 44 is provided at its rear with a horizontal recess 123 for the reception of the shank 133 of a grooving knife 131 which is semi-circular in shape, 100 the upper edges of the grooving knife being on a level with the cutting edge of the American channeling knife 44. The grooving knife 131 is located behind and as close as possible to the knife 44. With the construction and arrangement indicated a groove is cut at the base of the American channel. The grooving knife is of course withdrawn along with the American channel knife.

It may be of advantage to give the channeling knives a rapid reciprocatory or "jogging" movement of small amplitude, in the line of work feed, in order to assist in the cutting of the channel especially if there be, in addition to the channel knives, a chip removing or a grooving knife.

While it is preferred to attain the two-type-channelled sole by the use of two knives a somewhat similar result may be obtained by the use of one knife only as will now be described. For this purpose a knife such as that shown at 360 in Figs. 8 and 9 may be employed, the knife 360 being a compromise between the usual English and the usual American channel knife. As shown, the knife 360 is curved in a curve of large radius throughout or practically throughout its length, the part adjacent to its point being perhaps more nearly straight than the rest of the knife. This knife is mounted in a 120 125 130

slide movable in an arc as already described so that in one position it will cut a rather unusually flattened English channel and in a second position will cut a channel of the 5 American type although somewhat curved instead of straight. When put into this second position the knife may (e.g. by suitable disposition of the center of the arc) also have its point moved somewhat toward the median 10 line of the sole so that it will cut an American channel the base of which is further from the edge of the sole than is the base of the English channel which it cuts in its other position. Such a knife position changing 15 mechanism may be controlled manually or automatically as may be desired.

Another single-knife construction for channeling is illustrated in Fig. 11, in this case also the one knife 440 being a compromise. 20 The greater part of the edge of the knife 440 is straight like an American channel knife but the right-hand end is curved as shown at 442 into the English shape to adapt it to cut through the grain surface of the sole. 25 The edge guide 16 is so adjusted that when it is pressed to the left to the fullest extent (as it is normally) the sole will be held in such a position that the straight part only of the 30 knife will be active to cut the sole and therefore an American channel will be cut (in the waist). When the forepart is reached the edge guide 16 is moved (as by treadle mechanism hereinbefore mentioned) to the 35 right to a predetermined extent and consequently the sole, being pushed to the right to follow it, is as it were pushed further on to the knife so that the curved part 442 of the knife also is active and an English channel is cut. It will be observed, however, that 40 in this case the English channel is deeper than the American channel. With this construction the hereinbefore described rocking feathering knife may readily be used by coupling it to the edge guide treadle.

45 An alternative mechanism according to the invention admitting of obtaining with one knife two different shapes of channel at different parts of the one sole will now be described with reference to the diagram of 50 Fig. 10. In this case the knife 450 is a straight-edged channel knife of the usual American type adapted to cut an American channel as usual in the type of machine referred to. The machine is provided, however 55 (in addition to the usual feed wheel 12 and presser roll 18), with an auxiliary presser roll 180 adapted to act when desired on the grain surface of the sole margin and shaped to bend that margin in a curve in such a way 60 that the knife 450 will then cut into the bent sole from the grain surface instead of from the edge and will cut a channel which when the sole margin is again straightened appears 65 to be curved similarly to the usual English channel. The auxiliary presser roll 180 may

be thrown into action manually or automatically whenever it is desired to cut such an English channel.

Conveniently the auxiliary presser roll 180, when depressed to act upon the work, is depressed positively to a predetermined level, there being adjacent to the feed wheel 12 a work support 120 on which rests so much of the margin of the sole as requires to be bent down, the said work support 120 though urged yieldingly upwardly at that time being preferably when the auxiliary presser is not in action locked in position with its upper surface at the level of and forming a lateral extension of the feed wheel 12. 70 75 80

Having described my invention, what I claim as new and desire to secure by Letters Patent of the United States is:

1. That improvement in methods of channeling soles which consists in relatively moving a sole and means for channeling a sole to form a continuous channel in the sole, and changing the relation between the sole and the channeling means during the continuous channeling operation in such a manner as to 85 locate the channel in the sole face in one portion of the sole and in the sole edge in another portion of the sole.

2. That improvement in methods of channeling soles which consists in relatively moving a sole and means for channeling a sole to form a continuous channel in the sole, and shifting the channeling means edgewise of the sole during the continuous channeling operation to form the channel in the sole face 95 100 in one portion of the sole and to form the channel in the sole edge in another portion of the sole.

3. That improvement in methods of channeling soles which consists in relatively moving a sole and a channeling tool positioned to form a channel of a particular cross-sectional shape in one portion of the sole, shifting said tool into position to form a channel of a different cross-sectional shape, and 105 thereafter continuing said relative movement to form in another portion of the sole a channel of the cross-sectional shape of the first channel but continuous therewith.

4. That improvement in methods of channeling soles which consists in relatively moving a sole and a channeling tool to form an edge channel in one portion of the sole, changing the position of the tool and thereafter continuing the relative movement of 115 the tool and the sole to form a bottom channel in another portion of the sole, the shifting of the tool being timed with respect to the rate of relative movement of the sole and the tool to effect a gradual blending together 120 125 of the two channels.

5. That improvement in methods of channeling soles which consists in relatively positioning a sole and a channel knife for the cutting of a channel in the face of the sole, 130

5 relatively moving the sole and the knife to cut said channel in one portion of the sole, relatively repositioning the sole and the knife for the cutting of a channel in the edge of the sole, and thereafter continuing relatively to move the sole and the knife to form a channel of the last-mentioned type in another portion of the sole.

6. That improvement in methods of channelling soles which consists in positioning a channel knife for the cutting of an edge channel in a sole, feeding the sole past the knife to cut an edge channel in one portion of the sole, repositioning the knife for the 10 cutting of a bottom channel, and thereafter continuing to feed the sole past the knife to cut in another portion of the sole a bottom channel continuous with said edge channel.

7. That improvement in methods of channelling soles which consists in positioning a channeling knife for the cutting of an American channel in the margin of a sole, feeding the sole past the knife to form an American channel in one portion of the sole, shifting the knife into position for the cutting of an 20 English channel in the sole margin, and continuing to feed the sole past the knife both during and after said shifting movement to form in another portion of the sole margin 25 an English channel connected with the American channel.

8. That improvement in methods of channelling soles which consists in feeding a sole past an English channel knife while the tip 30 of the knife is operatively positioned to cut inwardly from the sole edge to form an American channel in the sole, shifting the knife into another position wherein the knife is adapted to cut inwardly from the face of 40 the sole while continuing to feed the sole, and feeding the sole further after shifting the knife thereby forming an English channel in another portion of the sole connected with the American channel.

45 9. That improvement in methods of channelling soles which consists in feeding a sole past a channel knife to form an American channel along the margin at one side of the shank portion of the sole, changing the position 50 of the knife and continuing to feed the sole to form an English channel around the margin of the forepart of the sole continuous with said American channel, and again changing the position of the knife and continuing to 55 feed the sole to form at the opposite side of the shank portion of the sole an American channel continuous with said English channel.

60 10. That improvement in methods of channelling soles which consists in feeding a sole past a knife positioned to cut a channel in the edge face of the sole, tilting the knife to continue the channel across the corner of the sole edge and into one side face of the sole, and thereafter continuing to feed the sole past 65

the knife to cut a channel in said side face of the sole continuous with the channel in said edge face.

11. That improvement in methods of channelling soles which consists in feeding the 70 marginal portion of a sole at one side of the shank past a channel knife constructed and arranged to cut a channel in the edge face of the sole, tilting the knife in one direction to continue the channel across the corner of the sole edge and into one side face of the sole, feeding the margin of the forepart of the sole past the knife to extend the channel in said side face around the forepart of the sole, tilting the knife in the opposite direction to continue the channel across the corner of the sole edge and into the edge face of the sole, and feeding the marginal portion of the sole at the opposite side of the shank past the knife to continue the channel in the edge face at 80 said side of the shank.

12. In a channelling machine, means for forming a continuous channel in a sole, and means for relatively positioning the sole and the channelling means during the continuous 90 channelling operation in a manner to cause the channelling means to enter different faces of the sole at different portions of the sole margin.

13. In a channelling machine, means for forming a continuous channel in a sole, and means for relatively positioning the sole and the channelling means edgewise of the sole during the continuous channelling operation to form the channel in one side face of the 100 sole in one portion of the sole margin and to form the channel in the edge face of the sole in another portion of the sole margin.

14. In a channelling machine, means for forming a continuous channel in a sole, and means for positioning the channelling means edgewise of the sole during the continuous channelling operation to vary the cross-sectional shape of the channel in different portions of the sole.

15. In a channelling machine, a channel knife capable of being positioned to cut both American and English channels, and operator-controlled means for adjusting the knife during operation of the machine.

16. In a channelling machine, channelling means, means for feeding a sole to the channelling means, and means for operating the channelling means while the sole is being fed to form along the shank and forepart of the sole a continuous channel which is of one cross-sectional shape in the shank and of another cross-sectional shape in the forepart.

17. In a channelling machine, channelling means, means for relatively moving the channelling means and the work in one direction to form a continuous channel in the work, and means operative during said relative movement for relatively moving the channelling means and the work in another direc- 125 130

tion to change the shape of channel being formed.

18. In a channeling machine, adjustable means for channeling and grooving a sole, means for feeding a piece of work to said means, and means for changing the adjustment of said means while the sole is being fed to vary the shape of channel being formed.

19. In a channeling machine, a channel knife adapted in one position to cut an American channel and in another position to cut an English channel in a sole, means for feeding a sole margin progressively past the knife, and means for shifting the knife from one position to another to vary the type of channel cut thereby.

20. In a channeling machine, a channel knife, and means for adjusting the position of the knife while a sole is being fed past it to effect edge channeling in one portion of the sole and bottom channeling in another portion of the sole.

21. In a sole channeling machine, a sole support, an adjustable channel knife, and means for adjusting the knife between two positions in one of which the knife is adapted to cut a channel in the edge of a sole on said support and in the other of which the knife is adapted to cut a channel in one side of said sole.

22. In a sole channeling machine, a tiltable channel knife, and means for tilting the knife from a position for channeling the sole edge to a position for channeling one side of the sole.

23. In a sole channeling machine, an adjustable channel knife normally positioned to cut inwardly from the edge of a sole, and means for repositioning the knife to cut inwardly from one side of the sole.

24. In a sole channeling machine, an adjustable channel knife normally positioned to cut inwardly from the edge of a sole, manually operable means for adjusting the knife to cut inwardly from one side of the sole, and means for restoring the knife to normal position.

25. In a sole channeling machine, a sole support, an adjustable knife carrier, a knife on said carrier adapted in one position of the carrier to cut a channel in the edge of a sole on said support and in another position of the carrier to cut a channel in one side of the sole, means normally holding the carrier in one of said positions, and operator-controlled means for shifting the knife carrier into the other of said positions.

26. In a channeling machine, two channeling knives normally positioned to co-operate in the cutting of an American channel in a sole, and means for repositioning said knives so that one only will operate thereafter to cut an English channel in the sole.

27. In a channeling machine, two knives capable of being positioned with portions of

their cutting edges substantially in line for the cutting of an American type channel in a sole, and means for retracting one of said knives from the sole and repositioning the other knife for the cutting of an English type channel in the sole.

28. In a channeling machine, a channel knife having a straight cutting edge adapted to cut inwardly from the edge of a sole to form an American channel in the sole, a second channel knife having a partially straight and partially curved cutting edge normally positioned to co-operate with the first knife in cutting the American channel, and means for withdrawing the first knife from the sole and repositioning the second knife to cut inwardly from one side of the sole to form an English channel in the sole.

29. In a sole channeling machine, means for supporting and feeding a sole, a knife shaped to cut an English channel in a sole, a second knife shaped to cut an American channel in a sole, and means for moving said knives into position to co-operate in cutting an American channel in one portion of a sole being fed through the machine and for retracting the second knife from the sole and repositioning the first knife for the cutting of an English channel in another portion of the sole.

30. In a sole channeling machine, means for supporting and feeding a sole, a knife shaped to cut an English channel in a sole, a tiltable carrier for said knife, a second knife movably mounted upon said carrier and shaped to cut an American channel in sole, means for tilting the carrier from a position in which the first knife is adapted to cut inwardly from the edge of a sole on said supporting means to a position in which said knife is adapted to cut inwardly from one side of the sole, and mechanism constructed and arranged to move the second knife relatively to the knife carrier into position to co-operate with the first knife in cutting inwardly from the edge of the sole and to retract the second knife from the sole when the first knife is positioned for cutting inwardly from the face of the sole.

31. In a channeling machine, means for feeding a sole, a channel knife adapted to be positioned for cutting a channel in the edge of the sole as it is being fed, means for varying the location of the channel widthwise of the sole edge, and means for shifting the knife into position to cut a channel in one side of the sole.

32. In a channeling machine, means for feeding a sole, a channel knife adapted to be positioned for cutting a channel in one side face of a sole as it is being fed, means for varying the location of the channel inwardly from the sole edge, and means for shifting the knife into position to cut a channel in the edge face of the sole.

33. In a sole channeling machine, means for feeding a sole, means for forming in the shank portion of the sole an American channel and for forming in the forepart of the sole an English channel continuous with the American channel, and means for reducing the thickness of the feather produced by the channeling operation. 5
34. In a sole channeling machine, means for feeding a sole, means for forming in the shank portion of the sole an American channel and for forming in the forepart of the sole an English channel continuous with the American channel, a knife for reducing the edge of the feather produced by the channeling operation, and means responsive to variations in sole thickness for adjusting the reducing knife to form a reduced feather of uniform thickness. 10
35. In a sole channeling machine, means for feeding a sole, means for forming in the shank portion of the sole an American channel and for forming in the forepart of the sole an English channel continuous with the American channel, an angularly adjustable feather edging knife for beveling the edge of the feather produced by the channeling operation, and means responsive to variations in sole thickness for angularly adjusting the feather edging knife to produce a feather of uniform thickness. 15
36. In a sole channeling machine, means for feeding a sole, means for forming in the shank portion of the sole an American channel and for forming in the forepart of the sole an English channel continuous with the American channel, a feather edging knife for beveling the edge of the feather produced by the channeling operation, and operator-controlled means for adjusting the reducing knife to vary the extent of feather reduction. 20
37. In a channeling machine, an adjustable channel knife for cutting channels of different types in the margin of a sole, an adjustable reducing knife for reducing to different extents the edge thickness of the sole, and connections between said knives constructed and arranged to adjust the reducing knife in accordance with the adjustment of the channel knife. 25
38. In a channeling machine, channeling means capable of adjustment to form channels of different types in different portions of a sole, adjustable means for reducing the thickness of the edge of the sole, and connections between the channeling means and the reducing means constructed and arranged to vary the extent of edge thickness reduction in accordance with the type of channel being formed by the channel knife. 30
39. In a sole channeling machine, means for feeding a sole, means for forming in the shank portion of the sole an American channel and for forming in the forepart of the sole an English channel continuous with the 35
- American channel, a feather edging knife for beveling the edge of the feather produced by the channeling operation, and connections between the reducing knife and the channel knife constructed and arranged to modify the action of the reducing knife upon the sole in accordance with variations in the type of channeling produced by the channel knife. 70
40. In a channeling machine, a channel knife capable of adjustment to cut channels of different types in a sole, a reducing knife capable of adjustment to reduce the sole edge thickness to different extents, and connections between the channel knife and the reducing knife constructed and arranged to adjust the latter for reducing the sole edge thickness to a predetermined extent when the channel knife is adjusted to cut one type of channel and to reduce the sole edge thickness to a different extent when the channel knife is adjusted to cut another type of channel. 75
41. In a channeling machine, channeling means, mechanism for adjusting the channeling means to form an American channel along one portion of the margin of a sole and to form an English channel along another portion of the sole margin, sole edge reducing means, and connections between said reducing means and the adjusting mechanism for the channeling means constructed and arranged to adjust the reducing means to provide maximum reduction at that portion of the sole margin where the American channel is formed. 80
42. In a channeling machine, an adjustable channel knife adapted in one position to cut an American type channel in one portion of a sole and in another position to cut an English type channel in another portion of the sole, an adjustable reducing knife movable to and from position for making a substantial reduction in the edge thickness of the sole, and connections between the channel knife and the reducing knife constructed and arranged to position the reducing knife for the making of a substantial reduction in sole edge thickness only when the channel knife is positioned to cut an American type channel. 95
43. In a machine for operating upon soles, adjustable sole edge reducing means, and mechanism operable for adjusting the reducing means during the normal operation of the machine to vary the extent of sole edge reduction independently of any variation in the thickness of the sole. 100
44. In a machine for operating upon soles, a feathering knife for beveling the edge of a sole, and mechanism for changing the angle of bevel of the cut made by the feathering knife during the normal operation of the machine and independently of any change in the thickness of the sole. 105
45. In a machine for operating upon soles, a sole edge reducing knife capable of being adjusted by the operator during normal 110
- 115
- 120
- 125

operation of the machine to vary the extent of edge reduction effected by the knife, and mechanism for adjusting the knife in accordance with variations in the thickness of the 5 body portion of a sole being operated upon by the knife.

46. In a machine for operating upon soles, a sole edge reducing knife, means for feeding a sole to the knife including a feed roll 10 movable in response to variations in the thickness of the work, a support for said roll, connections between said support and the reducing knife for adjusting the knife to vary the extent of sole edge reduction effected thereby 15 in accordance with variations in thickness of the body portion of the sole, and mechanism operable through said connections while the machine is running at normal speed to change the adjustment of the knife.

47. In a machine for operating upon soles, a tiltable edge beveling knife, means for feeding a sole to the knife, means responsive to variations in the sole thickness for tilting the knife to maintain uniform thickness at 25 the edge of the sole, and treadle-controlled mechanism for operating said means to tilt the knife.

48. In a machine for operating upon soles, adjustable sole edge reducing means, means 30 for feeding a sole to the reducing means, means responsive to variations in sole thickness for adjusting the reducing means, and means operable while the machine is running at normal speed for adjusting the reducing 35 means independently of variations in sole thickness.

49. That improvement in methods of fitting soles which consists in relatively moving a sole and means for channeling and edge-reducing a sole to form a continuous channel 40 in the sole and to reduce the edge thickness of the sole, and changing the relation between the sole and the channeling and edge-reducing means during a continuous channeling 45 operation in such a manner as to effect different types of channeling and different degrees of sole edge reduction in different portions of the sole.

50. That improvement in methods of fitting soles which consists in relatively positioning a sole and sole channeling and edge-reducing means for the cutting of a channel of a particular type and the effecting of a predetermined amount of reduction along the 55 margin of the sole, relatively moving the sole and said means to cut a channel of said type and to effect said amount of sole edge reduction in one portion of the sole, relatively repositioning the sole and said means for the cutting of a channel of a different type and the effecting of a different amount of sole edge reduction, and thereafter continuing relatively to move the sole and said means to form 60 a channel of the last-mentioned type and to

effect the last-mentioned amount of sole edge reduction in another portion of the sole.

51. That improvement in methods of fitting soles which consists in feeding a sole 70 past a channel knife and a beveling knife to cut a channel of a particular type in one portion of the sole margin and to bevel said portion of the sole margin at a particular angle, changing the position of said knives and feeding the sole past said knives as their 75 positions are being changed to extend the channel and to extend the bevel while gradually changing the channel from one type to another and while gradually changing the angle of the bevel, and continuing to feed the sole thereafter to cut in another portion thereof a channel of the last-mentioned type blended with the first channel by said channel extension and to form a bevel blended 80 with the bevel formed in the first portion of the sole margin by said bevel extension.

52. That improvement in methods of fitting soles which consists in feeding a sole 90 past an English channel knife and a beveling knife while the tip of the knife is operatively positioned to cut inwardly from the sole edge to form an American channel in the sole and while the beveling knife is positioned to effect a substantial amount of sole edge reduction, shifting said knives into positions 95 wherein the channel knife is adapted to cut inwardly from the face of the sole and the beveling knife is adapted to effect a lesser amount of sole edge reduction, and feeding the sole further after shifting the knives to form in another portion of the sole an English channel connected with the American channel and a less sharply beveled face connected with the more sharply beveled face.

53. That improvement in methods of fitting soles which consists in feeding a sole 100 past a channel knife and a beveling knife to form an American channel and a steeply inclined beveled face along one lateral margin of the shank portion of the sole, changing the position of said knives and continuing to feed the sole to form an English channel around the margin of the forepart of the sole continuous with said American channel and a less steeply inclined beveled face, and again changing the position of said knives and continuing to feed the sole to form at the opposite lateral margin of the shank portion of the sole an American channel 110 continuous with said English channel and a beveled face having an inclination corresponding to that of the beveled face at the lateral margin first operated upon.

In testimony whereof I have signed my 125 name to this specification.

ARTHUR BATES.
